PACKAGING

Carl J. Delegard, Chicago, Ill.

Application June 21, 1939, Serial No. 280,353

21 Claims. (Cl. 93—2)

My invention relates to packaging machinery of a type particularly suitable for completing the packaging of such articles as rolls of flexible felt roofing. It includes among its objects and advantages, a reduction in the complexity and number of parts involved, and simple and quick adjustment means for taking care of rather wide variations in the size of the package.

In the accompanying drawings:

Figure 1 is a side elevation partly in section 10 of a machine according to the invention;

Figure 2 is a plan view as on line 2—2 of Figure 1;

Figure 3 is an enlarged section of one of the end cover applicators;

Figure 4 is a view of the axial insert mechanism as on line 4—4 of Figure 1;

Figure 5 is a section along the axis of the main article carrier as on line 5—5 which appears in Figure 2 and in Figure 1; and

Figure 6 is a detail section as on line 6—6 of Figure 5.

In the embodiment of the invention selected for illustration, the machine comprises a structural frame made up of angle end beams 10 and side beams 12 and preferably supported on caster wheels 14. Substantially the right half of the frame as seen in Figure 1 is occupied by the main article carrier and associated parts which are supported on side plates 16. The left end of the machine is occupied by the paper magazine carrying the stack of wrapping paper 18. I provide a slightly inclined track or runway extending the entire length of the machine and interrupted only adjacent the main article carrier where the articles are picked up and transferred from the section of track leading into the main article carrier to the delivery section 20 best shown at the right end of Figure 1. This track is formed in part by the stack of wrapping paper 18 itself and completed by the incoming section 22 and the middle section 24. As indicated in Figure 2 I prefer to unite the sections 22 and 24 by side members 26 lying on either side of the wrapping paper stack 18.

In Figure 1 I have indicated one of the articles to be packaged 28, on which as yet no operation is being performed. It will be obvious that the section 22 may extend to the left indefinitely and that an indefinite number of articles 28 may lie on it ready to enter the packaging machine as the escapement means receives them.

The main drive for the entire machine is from the motor 31 through the gear reduction box 33 and sprocket drive at 34, which drives the main transmission shaft 35. In one set of satisfactorily operating machines I have operated the shaft 35 at twelve revolutions per minute. From the shaft 35 suitable transmission is provided for operating all the above mechanisms including the

inserting mechanism of Figure 4; the mechanism for applying adhesive to the wrapping paper; the escapement for periodically admitting an additional article at the proper time; and the main carrier for picking up the articles and spinning them to complete the packaging.

Adhesive application and wrapper pickup

Duplicate paste pots 38 are suspended pivotally on the ends of duplicate arms 40 rigid with parallel shafts 42 and 44 extending across above the path of the articles as they roll down the track. The shaft 42 is connected with the shaft 44 for rotation in unison therewith by the drag link 46 pivoted to the ends of duplicate arms 48 on the two shafts. Each paste pot contains a charge of fluid adhesive and at its bottom a dispensing roller 50 provided with a projecting tip 52 positioned to contact the top wrapper 18 and lift the roller 50 slightly in the paste container. This shifting movement each time the parts move into the position of Figure 1 causes a predetermined amount of adhesive to work down under the roller 50, and as the paste pot is lifted again the movement of the roller 50 back into contact with the bottom of the paste pot will expel a predetermined amount of adhesive through suitable openings along the bottom of the paste pot. In this way the lower outside surface of the paste pot receives a predetermined increment of adhesive during each cycle of operation, and movement of the paste pot down into contact with the paper as shown in Figure 1 will apply adhesive in narrow lines roughly indicated at 54 in Figure 2. The shafts 42 and 44 are given a reciprocating rotary movement by means of an arm 58 connected by a pitman 56 to a short crank 57 projecting from the end of the shaft 36.

It will be apparent that such a roll as 36 in Figure 1, when released by an escapement to be described hereinafter, will roll down of its own weight from the position shown in Figure 1 directly over the paper 18. As this roll strikes the first line of adhesive 54 it will adhere to and pick up the upper edge of the top wrapper, and its own rolling movement will roll the wrapper around the roll until the covered roll engages the lower paste line 54. At that point paste at the lower edge of the wrapper sticks the lower edge of the wrapper to a previous convolution of the same piece of paper and the roll moves on and into the position of the roll indicated in Figure 1 at 32 with a complete peripheral wrapping. As clearly indicated at 56 in Figure 5, this peripheral wrapping does not extend beyond the ends of the roll itself.

Escapement

Rigid with the shaft 42 is a release lever 58 which constitutes the primary escapement for releasing the roll 36 at the proper time. Rota-

tion of the shafts 42 and 44 in counterclockwise direction from the position of Figure 1 will move all the arms 40, 48, and 58 and lift the paste pots 38 far enough to clear the roll 30 as it slips out from under the release arm 58 and rolls down the track. Also rigid with the shaft 42 is the hold back segment 60, which will move down in front of the roll 28 simultaneously with the lifting of the release arm 58 and block the forward movement of the roll 28 until the parts come back again almost to the position of Figure 1 at which time it will move high enough up to let the next roll roll down against the arm 58.

Inserts

It is customary to sell roll roofing with a small package or carton of roofing nails and a small can of roofing cement housed inside each roll. The camshaft 62 (see Figures 1 and 4) is driven at the same speed as the shaft 36 by suitable means such as the sprocket 64 on the shaft 36 connected by the chain 66 to the sprocket 68 on shaft 62, and supported from the main frame in any suitable way as by bearing brackets 70. At each end of the shaft I provide an actuating lever 72 journaled on a fixed stud 74 and carrying a contact roller 76 pressing against the edge of an annular cam 78 mounted on the end of the shaft 62. At either end of the roll 30 I provide a magazine 73. One of the magazines may contain cans 75 of roofing cement and the other magazine may contain packages 77 of roofing nails. At the bottom of each magazine I provide a window 80 positioned to register with the hollow space at the center of the roll 30 when in the position of Figure 1. The upper end of the lever 72 is bifurcated at 82 to engage and actuate the pins 84 integral with the followers 86 which are resiliently pressed toward the center of the machine by springs 88, both followers and springs being housed in suitable housings 90. At the moment when the shafts 42 and 44 pause in the position of Figure 1 because the crank 58 is on dead center, the steeply inclined surface portion 92 of the cam 78 moves across in front of the roller 76 and the spring 88 is permitted to expand and expel the lowest insert 75 or 77 into the roll 30. Thereafter, while the roll 30 goes on its way through the machine, the gently inclined cam surface 94 forces the lever 72 back into the position of Figure 4 and the stack of inserts in each of the magazines 73 drops down ready for the next cycle of operation.

Wrapper feed

The stack of wrappers 18 is supported on a platform 96 mounted for vertical sliding movement and actuated by racks 98 extending downward below the platform. Each rack 98 may be elevated by a gear 100 meshing with it. Directly opposite each gear 100 I provide an idle abutment roller 102 to properly guide the movement of the parts. The gears 100 are connected for rotation in unison as by a sprocket chain 104. I have provided a speed-reducing transmission from the shaft 36 comprising a small sprocket 106 (see Figure 2) driving a large sprocket 108 on a suitable countershaft. The large sprocket 108 is integral with the small sprocket 110 which drives the large sprocket 112 on the shaft 36. The sprocket 112 is free to rotate on the shaft 36 and is integral with the eccentric 114 which actuates the eccentric rod 116. The eccentric rod 116 reciprocates the lever 118 which carries the pawl 120 engaging the teeth of a large

75 ratchet 122 axial with and integral with the adjacent gear 100. A suitable holding pawl 124 completes the transmission.

Spinning

5 The main article carrier comprises parts mounted for simple rotation and for planetary rotation about the transfer shaft 126 which is driven from the shaft 36 at one-fourth the speed of the shaft 36 as by means of the sprocket drive 10 at 128 and this shaft is journaled in the stationary end plates 16. Referring chiefly to Figures 2 and 5, the article carrier proper comprises two pairs of spiders each having four radial arms. 15 The first pair of spiders 130 is rotatably mounted on the shaft 126 as by means of the sleeves 132. The second or inner pair of spiders 134 is rigid with sleeves 136 rotatable on the sleeves 132. Each pair of spiders carries four planetary rollers 138 rotatable on axes parallel to the axis of the shaft 126. All eight of the planetary rollers carry pinions 140 at one end and all these pinions mesh with a gear 142 suitably driven from the shaft 36 at substantially the same speed as the shaft 36, as by the sprocket drive 144. With the two sets of spiders rigidly locked in the relative positions illustrated in Figure 1, it will be apparent that all the planetary rollers 138 will be in rotation counterclockwise as indicated by the arrows in Figure 1, and that the roll 30 coming down the track in clockwise rotation will move into a position just a trifle lower than the position indicated at 32 in Figure 1, if the parts are properly timed, and will be continued in its rotation by its contact with the planetary rollers 138 while it is carried from the position at 32 in an arcuate path around the axis of the shaft 126 to the discharge position at 146.

20 To take care of articles of different size it is necessary to be able to vary the relative positions of the planetary rollers 138 to vary the width of the opening between the pairs of rollers that receive the article 32. For this purpose I provide a gear 148 rigid with the sleeve 132 and a gear 150 rigid with the sleeve 136. 25 Adjacent the sleeves 132 I provide arms 156 keyed on the shaft 126. The arms carry a cross shaft 154. The ends of the cross shaft 154 project on through the arms 156 adjacent the gears 148. Each projecting end of the shaft 154 carries a pinion 158 meshing with the adjacent gear 150 and a pinion 160 meshing with an intermediate pinion 162 journaled on a stud shaft 164 in the arm 156. The pinion 162 in turn meshes with the gear 148. By reference to the showing 30 of these parts in Figure 1, it will be apparent that when the shaft 126 is stationary and adjustment is made by rotating the shaft 154, the pinions will rotate the gears 148 and 150 in opposite directions so as to move the rollers 138 shown in Figure 1 supporting the roll at 32 toward or away from each other. By proper selection of gear ratios these movements can be made equal, so that the axis of the roll 30 is not shifted around the shaft 126 when adjustment is made. To adjust the shaft 154 and clamp it in adjusted position I provide suitable means in the form of an arm 151 rigid with the shaft 154 and an anchor 152 on shaft 126 having a slotted arm 153 to which the arm 151 may be bolted by the bolt 155.

Edge wrapping

35 Adjacent the path of each end of the spinning article 32 on its way to position 146 I provide a holder 166. On this holder I provide first, a

series of idle rollers 170 for applying edge tape. The tape is housed in a suitable supply roll at 172 and drawn over the roller 174, which dips into the adhesive bath at 176 and applies adhesive to the tape. It then passes down and around the first roller 170 being held in contact therewith by an idler 178. It will be apparent that as the article 32 moves from the position of Figure 1 past the various rollers 170, it will wind the tape 172 around itself. When the article has progressed to substantially the next to the last roller 170, it may complete a suitable electric contact 179 to actuate the solenoid 180, which solenoid actuates a lever pivoted at 182, which lever carries a cutting knife 184 at its left end. The actuation of the solenoid will throw the cutting knife down to strike a sharp blow against the article and sever the tape 172. It will be apparent that the position of the knife 184 is such that this severance will leave a short reach of tape hanging down between the idler roller 178 and the adjacent roller 170 ready to be contacted by the next article as it enters.

This leaves the tape with half its width wrapped on the article 32 and the other half projecting as indicated in dotted lines at 186 in Figure 5. Immediately thereafter, the article, while still spinning, encounters the crimping rollers 187 of which there are two, each journaled in vertical slots 190 in the carrier plates 192 so that they rest by their own weight on the article and are rotated by frictional contact therewith. Each crimping roller comprises a tube 194 carrying metal heads 196 at its ends and felt discs 188 projecting beyond metal heads 196. The whole is journaled on the pivoted shaft 206, the ends of which ride in the slots 190. It will be apparent that as the article moves under the two rollers 187, the projecting portion of the tape at 186 will be spun down to the position indicated in full lines in Figure 5.

The tape 172 is cut on a bias so that it folds down readily without material or objectionable wrinkling or folding. To make sure that the felt discs 188 do not stick to the tape, at least the first discs 188 are provided with a stationary separator blade. I have indicated said blades for both sets of discs 188. The blade proper has its sharp leading edge positioned as indicated at 181 in Figure 1. The body of the blade at 183 lies against part of the working face of the disc 188, and when a roll 32 is present its other face may have light sliding contact with the tape 172. The blade is supported by a frame member 185, journaled at 187 on the rod 200, and prevented from rotating by a rigid finger 189 entering a vertical slot 191 in the supporting plate 168.

To take care of rolls 32 of different sizes, the plate 168 has end lugs 193 overlying stationary bosses 195 on brackets projecting from the end plates 16, and is guided in vertical adjustment between the bosses 195 by vertical edge portions 197 contacting the bosses. Set screws 199 enable the operator to raise and lower the plate 168 to position it so that the roll 32 will press against the idle rollers 170 with an adequate force. The weight of the plates 168 and of the parts carried by the plates may be made such as to generate the exact force desired for the working pressure of rollers 170, in which case the operator adjusts the set screws 199 so that each roll 32 barely lifts the set screws off the bosses 195. Thus the force used is accurately determined and if any individual roll 32 should happen to be

a trifle oversize, it will be handled without difficulty, as the plates 168 will merely be lifted an additional fraction of an inch as that particular roll 32 passes under the idle rollers 170.

5 End covers

Before the edge tape 172 is applied, I position a cardboard cover disc 202 over each end of the article. The container 204 for the discs 202 is shown in Figure 1 and its position is indicated in dotted lines in Figure 2. To transfer one of the discs 202 from the container to the end of the article, I provide a carrier plate 206 rotating in unison with the shaft 126 and carrying four pneumatic pickers 208, each in axial alignment with the article 32 during its spinning.

Each picker comprises a main housing 210 suitably mounted on the plate 206. Inside the housing is a plunger 212 normally held in the position of Figure 3 by coil spring 214. At its rear end, the plunger carries a leather sealing cup 216 slideable in the housing 210, and a projecting head 218 extending beyond the housing 210 for contact with actuating cam members to be described hereinafter. The plunger is actuated by suction supplied through the connection at 220 forming part of a manifold 222 in open communication with ports 224. In the position of rest indicated in Figure 3, the ports 224 are covered by the end 226 of a half length sleeve 228, which end is provided with a pair of piston rings 230 to improve the seal. From the annular space between the housing 210 and the sleeve 228, vacuum becomes effective inside the entire housing through ports 232 communicating with the main space inside the housing, and the same suction is effective inside the tubular plunger rod 212 by reason of ports 234 in the plunger rod. At its front end the plunger rod 212 passes through a suitable packing 236, and at its outer end carries a flexible suction cup 238 suitably swiveled about the axis of the plunger as by means of a metal ferrule 240 riding under the flange 242 of a metal ring held in place on the end of the plunger by the nut 244. The hollow rod 212 is open at its right end, as seen in Figure 3, so that only partial suction is effective in housing 208 by the throttling action of ports 234, until a cardboard disc covers the cup 238 and completes the seal.

Referring now to Figures 2 and 5, as each picker comes into register with the end cap 202 it is cammed axially toward the center of the machine by suitable means such as the cam 246 mounted on the stationary end plate 16. This initial displacement uncovers the ports 224, and the plunger immediately moves over and thrusts its suction cup against the adjacent piece of cardboard. Continued rotation of the plate 206 carries the piece of cardboard up almost to the position indicated at 32 in Figure 1, and during this movement of the plate 206, further inward movement of the plunger is restrained by a second cam 248, the edge of which lies in front of the head 218. At or a trifle above the position 32 as the tape 172 is starting to wind onto the article, the head 218 passes out beyond the end of the cam 248 and the suction promptly moves the plunger over the rest of the way, pressing the end piece 202 against the end of the article where it remains under pressure from the plunger until after the rollers 188 have completed the edge seal and wrapped the tape down over the edge of the disc 202. Thereafter, at any convenient point between the last roller 188 and

the position of the article at 146, the suction delivered to the connection 220 is cut off and the picker promptly moves back to retracted position under the force of spring 214 ready for a second cycle of operations.

To deliver suction to the connection 220 with proper timing, I provide tubes 250 running in from all the pickers to a central manifold 252 rigidly attaching to and turning with the plate 206. The stationary bearing 254 for the shaft 126 carries a plate 258. The timing valve 258 lies against the manifold 252 and is pressed against it by the springs 260 and guided by the bolts 262 housed in the springs 260 and passing through suitable apertures in the plate 258. Each connecting tube 250 is in communication with an L-shaped passage 264 debouching at the contact surface of the manifold 252, and the valve 258 receives suction from any suitable source through a conduit 266 which communicates with an arcuate valve port 268 to deliver suction to the conduit 250 beginning slightly before the time when the cam 246 kicks the plunger into operative position, and continuing throughout the movement of the picker past the cam 248 and the rollers 187.

It will be obvious that while I have illustrated rolls of roofing and wrapping paper suitable for such rolls, the principles of my invention are applicable to the packaging of articles of all sorts and sizes, including such items as foods, and pharmaceutical products in all sizes, and such wrapping materials as cloth, Cellophane, or oiled paper.

Without further elaboration the foregoing will so fully explain my invention that others may, by applying knowledge current at the time of application, readily adapt the same for use under various conditions of service.

I claim:

1. Packaging machinery comprising means for rotating a cylindrical article; peripheral wrapping means for positioning wrapping material around the body of said article; a second peripheral wrapping means for positioning a peripheral strip of material around each end of said article with an edge projecting beyond the end of said article; means for positioning an end cover against the end of said article and means for subsequently crimping the projecting edge portion of said peripheral strip of material over said end cover.

2. Packaging means for cylindrical articles, including: a plurality of pairs of supporting rolls mounted for rotation side by side on spaced parallel axes; movable support means for supporting and moving said pairs of rolls laterally in a closed path during a portion of which path said rolls are suitably positioned to receive and support a cylindrical article resting on them by gravity and too large to fall between them; means operative during a period when said article is supported by said rolls, for rotating said article in such a sense that its surface remote from said rolls travels in the same direction as the lateral movement of said rolls and article; wrapping material supply means exposing wrapping material in a position to be contacted by said article and entrained and wrapped around said article by the rotation of said article; picker means associated with each pair of rolls and in axial alignment with the axis of the article carried by said rolls for positioning an end cover against said article while it is carried by said

rolls; and turning-in means positioned to act on said article and its peripheral wrapping after said picker means has positioned its end covers, to turn in the edge of said peripheral wrapping

means down over the peripheral edge of said end cover; and adjustment means for simultaneously varying the lateral spacing of all said pairs of rolls to adapt them to handle articles of different sizes.

3. Packaging means for cylindrical articles, including: a plurality of pairs of supporting rolls mounted for rotation side by side on spaced parallel axes; movable support means for supporting and moving said pairs of rolls laterally in a closed path during a portion of which path said rolls are suitably positioned to receive and support a cylindrical article resting on them by gravity and too large to fall between them; means operative during a period when said article is supported by said rolls, for rotating said article in such a sense that its surface remote from said rolls travels in the same direction as the lateral movement of said rolls and article; wrapping material supply means exposing wrapping material in a position to be contacted by said article and entrained and wrapped around said article by the rotation of said article; positioning means associated with each pair of rolls and in axial alignment with the axis of the article carried by said rolls for positioning an end cover against said article while it is carried by said rolls; and turning-in means positioned to act on said article and its peripheral wrapping after said positioning means has positioned its end covers, to turn in the edge of said peripheral wrapping means down over the peripheral edge of said end cover.

4. Packaging means for cylindrical articles, including: a plurality of pairs of supporting rolls mounted for rotation side by side on spaced parallel axes; movable support means for supporting and moving said pairs of rolls laterally in a closed path during a portion of which path said rolls are suitably positioned to receive and support a cylindrical article resting on them by gravity and too large to fall between them; means operative during a period when said article is supported by said rolls, for rotating said article in such a sense that its surface remote from said rolls travels in the same direction as the lateral movement of said rolls and article; wrapping material supply means exposing wrapping material in a position to be contacted by said article and entrained and wrapped around said article by the rotation of said article; picker means associated with each pair of rolls and in axial alignment with the axis of the article carried by said rolls for positioning an end cover against said article while it is carried by said rolls; and turning-in means positioned to act on said article and its peripheral wrapping after said picker means has positioned its end covers, to turn in the edge of said peripheral wrapping means down over the peripheral edge of said end cover; and adjustment means for varying the lateral spacing of said pairs of rolls to adapt them to handle articles of different sizes.

5. Packaging means for cylindrical articles, including: a plurality of pairs of supporting rolls mounted for rotation side by side on spaced parallel axes; movable support means for supporting and moving said pairs of rolls laterally in a closed path during a portion of which path said rolls are suitably positioned to receive and support a cylindrical article resting on them by gravity and

too large to fall between them; means operative during a period when said article is supported by said rolls, for rotating said article in such a sense that its surface remote from said rolls travels in the same direction as the lateral movement of said rolls and article; wrapping material supply means exposing wrapping material in a position to be contacted by said article and entrained and wrapped around said article by the rotation of said article; positioning means associated with each pair of rolls and in axial alignment with the axis of the article carried by said rolls for positioning an end cover against said article while it is carried by said rolls; and turning-in means positioned to act on said article and its peripheral wrapping after said positioning means has positioned its end covers, to turn in the edge of said peripheral wrapping means down over the peripheral edge of said end cover; and adjustment means for varying the lateral spacing of said pairs of rolls to adapt them to handle articles of different sizes.

6. Packaging means for cylindrical articles, including: a pair of supporting rolls mounted for rotation side by side on spaced parallel axes and positioned to receive and support a cylindrical article resting on them by gravity and too large to fall between them; means for rotating said article and rolls; wrapping material supply means exposing wrapping material in a position to be contacted by said article and entrained and wrapped around said article by the rotation of said article; positioning means associated with said rolls and in axial alignment with the axis of the article carried by said rolls for positioning an end cover against said article while it is carried by said rolls; and turning-in means positioned to act on said article and its peripheral wrapping after said positioning means has positioned its end covers, to turn in the edge of said peripheral wrapping means down over the peripheral edge of said end cover.

7. Packaging means for cylindrical articles, including: a set of supporting rolls mounted for rotation side by side on spaced parallel axes and suitably positioned to receive and support a cylindrical article resting on them by gravity; means for rotating said article and rolls; wrapping material supply means for delivering wrapping material to be entrained and wrapped around said article by the rotation of said article; means in axial alignment with the axis of the article carried by said rolls for positioning an end cover against said article while it is carried by said rolls; and turning-in means positioned to act on said article and its peripheral wrapping after said positioning means has positioned its end covers, to turn in the edge of said peripheral wrapping means down over the peripheral edge of said end cover.

8. Packaging machinery, comprising: a rotating shaft; a first set of rolls each rotatable on an axis parallel to said shaft and laterally offset therefrom; said rolls being uniformly spaced around said shaft and all at the same radial distance from said shaft; a pair of end members rotatably supported on said shaft and in turn rotatably supporting the ends of said rolls; a second set of rolls equal in number to said first set; a second pair of end members rotatably supported on said shaft and rotatably supporting said second set of rolls; said second set of rolls being all at the same radial distance from said shaft as said first set; a drive member keyed to said shaft; drive connections from said drive

member to each of said pairs of end members; picker means rotating with said shaft for positioning end covers on articles carried by said rolls; a planetary transmission for rotating all the rolls of both sets, all in the same sense; and unitary adjustment means for adjusting said drive connections to move said sets of rolls and vary the angular positions of both sets equally in opposite directions with respect to said drive means; whereby adjustment may be made without changing the relative alignment of said pickers and an article supported between two rolls of different sets.

9. Packaging machinery, comprising: a rotating shaft; a first set of rolls each rotatable on an axis parallel to said shaft and laterally offset therefrom; said rolls being uniformly spaced around said shaft and all at the same radial distance from said shaft; a pair of end members rotatably supported on said shaft and in turn rotatably supporting the ends of said rolls; a second set of rolls equal in number to said first set; a second pair of end members rotatably supported on said shaft and rotatably supporting said second set of rolls; said second set of rolls being all at the same radial distance from said shaft; a drive member keyed to said shaft; drive connections from said drive member to each of said pairs of end members; means rotating with said shaft for positioning end covers on articles carried by said rolls; a planetary transmission for rotating all the rolls of both sets, all in the same sense; and unitary adjustment means for adjusting said drive connections to move said sets of rolls and vary the angular positions of both sets equally in opposite with respect to said drive means; whereby adjustment may be made without changing the relative alignment of said positioning means and an article supported between two rolls of different sets.

10. Packaging machinery, comprising: a rotating shaft; a first set of rolls uniformly spaced around said shaft and all at the same radial distance from said shaft; a pair of end members rotatably supported on said shaft and in turn rotatably supporting the ends of said rolls; a second set of rolls equal in number to said first set; a second pair of end members rotatably supported on said shaft and rotatably supporting said second set of rolls; said second set of rolls being all at the same radial distance from said shaft; a drive member keyed to said shaft; drive connections from said drive member to each of said pairs of end members; means rotating with said shaft for positioning end covers on articles carried by said rolls; and unitary adjustment means for adjusting said drive connections to move said sets of rolls and vary the angular positions of both sets equally in opposite directions with respect to said drive means; whereby adjustment may be made without changing the relative alignment of said positioning means and an article supported between two rolls of different sets.

11. Packaging machinery, comprising: a rotating shaft; a pair of parallel rolls each rotatable on an axis parallel to said shaft and laterally offset therefrom; end members rotatably supported on said shaft and in turn rotatably supporting the ends of said rolls; means rotating with said shaft for positioning end covers on articles carried by said rolls; a transmission for rotating said rolls; and unitary adjustment means for adjusting said rolls to move them both by equal increments toward or away from each

other; whereby adjustment may be made without changing the relative alignment of said positioning means and an article supported by said rolls.

12. Packaging machinery, comprising: means for supporting a cylindrical article to be packaged and simultaneously rotating it about its axis and moving it laterally in a predetermined path of lateral movement; a wiper mechanism positioned above and adjacent the path of lateral movement; said wiper mechanism including a first set of idle rollers for peripheral contact with the article and a second set of idle turning-in rollers having flange portions adapted to act on the end portion of a peripheral wrapper extending axially beyond the end of said article and turn said end portion into the plane of the end of the article; support means for all said rollers holding said rollers, when inactive, slightly below operating position; said rollers all being free to rise above their supports, whereby the weight of each roller and associated parts, determines the effective pressure of said roller on the article.

13. Packaging machinery, comprising: means for supporting a cylindrical article to be packaged and simultaneously rotating it about its axis and moving it laterally in a predetermined path of lateral movement; a wiper mechanism positioned above and adjacent the path of lateral movement; said wiper mechanism including a roller for contact with the article; support means for said roller holding said roller, when inactive, slightly below operating position; said roller being free to rise above its support, whereby the weight of said roller and associated parts determine the effective pressure of said roller on the article.

14. The method of packaging cylindrical articles, which comprises: rotating the article about its own axis; positioning a peripheral wrapper on the cylindrical article surface up to but not beyond the end edge of the article; positioning an end cover against each end of the article while the article continues to rotate; positioning bias cut edge tape entrained by the rotation of the article, with part of its width adhered to the peripheral wrapper and part projecting axially beyond the end of the article; and spinning the projecting portion of said edge tape down over the peripheral edge of said end cover.

15. The method of packaging cylindrical articles, which includes: rotating the article about its own axis; positioning bias cut edge tape entrained by the rotation of the article, with part of its width adhered to the periphery of the article and part projecting axially beyond the end of the article; and spinning the projecting portion of said edge tape down over the end face of the article.

16. Packaging means for rolls of flexible roofing material, comprising, in combination: means for wrapping a cylindrical paper wrapper around the cylindrical exterior of the roll with its edges terminating at least short of projecting beyond the plane of the end of the roll; means for positioning a relatively stiff disc-like end closure against each end of the roll; means for wrapping a flexible corner strip to bind the edges of said wrapper and project in cylindrical shape past the plane of the end of the roll; and means for

crimping the projecting portion of each said corner strip down into the plane of the adjacent end closure and into engagement with an annular peripheral portion of said end closure.

17. Packaging means for articles of cylindrical shape, comprising: a first means for encircling the cylindrical periphery of the article with a wrapper which does not project beyond the end of the article; a second means for placing an end closure against each end of the peripherally wrapped article, and temporarily holding the same in place while the article revolves about its own axis; a third means for affixing in cylindrical form to the peripheral wrapping, another narrow wrapping, overlapping the peripheral wrapping and projecting beyond the end of the article; and a fourth means for crimping the projecting portion of said narrow wrapping over onto said end closure and affixing said narrow wrapping to said end closure before said second means ceases to hold said end closure in place.

18. Packaging means for articles of cylindrical shape, comprising: a first means for encircling the cylindrical periphery of the article with a wrapper which does not project beyond the end of the article; a second means for placing an end closure against each end of the peripherally wrapped article, and temporarily holding the same in place while the article revolves about its own axis; a third means for affixing to the peripheral wrapping another narrow wrapping, overlapping the end of the peripheral wrapping and projecting beyond the end of the article; and a fourth means for crimping the projecting portion of said narrow wrapping over onto said end closure and affixing said narrow wrapping to said end closure before said second means ceases to hold said end closure in place.

19. The method of packaging a cylindrical flat-ended article which includes: encircling the cylindrical periphery of the article with a flexible first covering element; placing a second plane covering element against the end of the article; encircling the periphery of the article adjacent the circular edge where the end surface and the cylindrical surface meet, with a third flexible covering element, and affixing said third covering element to said first covering element in a position such that it projects beyond the end of the article; crimping the projecting portion of said third covering element into contact with said second covering element; and affixing to said second covering element the overlapping portion of said third covering element.

20. The method of packaging a cylindrical flat-ended article which includes: encircling the cylindrical periphery of the article with a flexible first covering element; encircling the periphery of the article adjacent the circular edge where the end surface and the cylindrical surface meet, with a second flexible element, and affixing said second covering element to said first covering element in a position such that it projects beyond the end of the article; crimping the projecting portion of said second covering element over the end of said article; and fastening the crimped-over portion of said second element in place.

21. A method according to claim 20 including the step of rotating the article about its own axis while applying said covering elements.

CARL J. DELEGARD.
